W. Randolph Jr.

United States Patent Office.

A. FARROW, OF CARROLLTON, ILLINOIS.

Letters Patent No. 73,707, dated January 28, 1868.

IMPROVEMENT IN GANG-PLoughs.

The Schedule referred to in these Letters Patent and making part of the same.

TO ALL WHOM IT MAY CONCERN:

Be it known that I, A. FARROW, of Carrollton, in the county of Greene, and State of Illinois, have made certain new and useful Improvements in Gang-Ploughs; and I do hereby declare that the following is a full and clear description thereof, reference being had to the accompanying drawings, and to the letters of reference marked thereon.

The object of this invention is to construct a gang-plough in such a manner that the depth of furrow may be regulated at pleasure by the driver, and this he will do by elevating or depressing the point or toe of the machine at pleasure.

The plough-beams are attached to the axle, by means of draught-links and clevises, and each of the beams has an independent lever for each of its ends, by means of which to apply to them the requisite movement.

To enable those skilled in the art to make and use my improved plough, I will proceed to describe its construction and operation.

Figure 1, of the drawings, is a longitudinal sectional elevation of the improved machine.

Figure 2 is a plan of the same.

This machine, like all other gang-ploughs, has a frame, A, which is mounted on the wheels A¹ and axle A². On top of the frame A is the driver's seat S, upon which the operator rides and manages the whole machine. There are two plough-beams, B B, which are attached to the back side of the axle by means of clevises b and links b¹. The links b¹ should be, say, three or four inches long, more or less, so as to allow the front end of the beam to be raised or lowered, as shown by the dotted lines b² in fig. 1. In order to give to the ploughs B' an independent motion in a vertical direction, so as to elevate or depress either the point or heel, as may be desired, each beam is provided with two levers C C', which may be operated so as to give the required elevation or depression of either end. The lever C is fulcrumed to the side of the frame A at x, and is connected with the bolt x', which couples the clevis b with the link b¹ by means of the link c. A tooth or rib, on the inside of the lever C, engages the cogged rack c¹, affixed to the side of the frame A, and holds the said lever in any required position. The lever is allowed a sufficient amount of lateral spring to disengage it from its fastening in the rack c¹. When the lever C is raised up, as shown in full lines in fig. 1, the front end of the beam and the point of the plough will be up, as shown in full lines; but when the lever is thrown down, as indicated by dotted lines in the same figure, the front end of the beam and the plough-point will be made to assume the position indicated by dotted lines b², also of fig. 1. The lever C' is fulcrumed to the frame A at x², and it is connected by means of the arms C² and c² with the sector C³. The periphery of this sector is cogged, and gears into the vertical rack C⁴, the lower end of which is attached to the rear end of the plough-beam B. The sector-journal c³ finds its bearing in the frame A, and the horizontal arm C³ carries a sheave or roller, c⁴, that guides and steadies the upper end of the rack C⁴. A lug, e⁵, is affixed to the side of the frame A, so as to engage the teeth of the cogged rack c⁶ on the inside of the arm C², as shown best in fig. 2. By this means the lever C' is held forward or backward in any required position. When thrown back, the lever, sector, and plough will appear as they are shown by the full lines in fig. 1; but when the lever is thrown forward, the parts will assume the positions of the dotted lines c'. By this means the ploughs will be made to assume any required position, and may be entirely raised out of the ground, or set so as to run more or less deep, as circumstances may require. The lever C' is to be constructed in such a manner as to allow it to spring laterally far enough to disengage the rack c⁶ from the lug e⁵, in the same manner that the lever C is disengaged from its fastenings. Both of the lever-handles are to be placed within easy reach from the driver's seat.

Having described my invention, what I claim, is—

1. The combination and arrangement of the lever C, link c, and traction-connections b b¹ herein shown and described.
2. I claim the lever C¹, arm C², sector C³, rack C⁴, and plough-beam B, when combined and operated substantially in the manner and for the purpose herein shown and described.

In testimony of which invention, I hereunto set my hand in presence of—

A. FARROW.
